DOLL WALKER UNIT

Robert Gardel, 11 Riverside Drive, New York, N.Y.
Filed July 5, 1969, Ser. No. 40,655
6 Claims. (Cl. 46—149)

This invention relates to a doll walking mechanism, and particularly to a simple and efficient mechanism for operatively interconnecting the legs of a doll so that the movement of either leg causes corresponding movement of the other leg in the opposite direction.

It is an object of the invention to provide such a mechanism which can be installed quickly and easily in hollow plastic bodies which may vary slightly in their critical dimensions; that is, in which strict tolerances need not be observed.

A further object is to provide such a mechanism in which each leg can be moved to a kicking or sitting position.

Another object is to provide such a mechanism in which each leg is snap-fitted into a body opening as the sole connection between the leg and the body, and in which the mechanism parts permitting movement between standing or walking position and kicking or sitting position are carried entirely by the leg to which they relate.

The mechanism has proved to be particularly suitable for use in relatively large dolls, standing 30 inches or more in height, but it could well be adapted for use in smaller dolls if desired.

A practical embodiment of the invention is shown in the accompanying drawings, in which:

FIG. 1 represents a front elevation of a doll body and legs, parts being broken away and parts being in section;

FIG. 2 represents a vertical section on the line II—II of FIG. 1, parts being broken away and the leg being shown in three positions corresponding to a walking step;

FIG. 3 represents an exploded perspective view, partly in section, of the walking lever mounting disc;

FIG. 4 represents a detail perspective view of the rocker, walking levers and part of the rocker rod; and

FIG. 5 represents a perspective view of the neck cap.

Referring to the drawings, the molded plastic body 1 is shown as having a neck opening 2 (inwardly flanged at 3), and circular leg openings lying in planes which slant between 30° and 45° from the vertical and bounded by fairly sharp edges 4, 5 uniformly V-shaped in radial section. Each leg 6, 7 has at its top a correspondingly slanted circular opening, around which is an outwardly projecting annular lip or bead 8, 9 forming with the adjacent surface of the leg a V-shaped groove complementary to the edge 4 or 5 of the respective leg opening. The plastic material of which the body and legs are made has sufficient resiliency or elasticity to permit the lips or beads 8, 9 to be snapped into place in the body openings, with the edges of the openings engaging in the grooves on the legs, but this operation requires considerable force and, conversely, the legs cannot easily be snapped out of their engagement with the body. The fit is easy but not loose, so that the legs can be moved readily to desired positions but do not wobble.

The walking mechanism includes, for each leg, a metal disc 10 having a diameter greater than that of the opening in the leg but no greater than that of the lip or bead (8 or 9), the disc having a plurality of fingers 11 stamped so as to project downwardly within the opening in the leg and with their ends bent out to engage the material of the leg around the periphery of said opening, as clearly shown in FIG. 1. A lever 12, having a lower part 12' lying parallel to the plane of the disc 10 and an upper part 12" extending in a substantially vertical direction, is connected to the disc by means of a pin 13

2

having a head 13' on one end and having its other end staked or otherwise secured in a hole 14 in the center of the disc. The pin passes through a hole in the part 12' of the lever 12 and passes also through a washer 15 lying between the lever 12 and the disc, the washer being riveted to the part 12' of the lever by rivets 16 the heads 16' of which are rounded and project below the washer. The disc 10 is provided with one or more holes or depressions 17 spaced from the hole 14 by a distance equal to the distance of the rivets 16 from the pin 13 and located at points corresponding to desired positions of the leg, e.g., standing (walking) or sitting, as explained below. A spring 18 surrounds the pin 13, bears against the under side of the head 13' and urges the lever 12 and washer 15 strongly toward the disc 10.

The vertical parts 12" of the levers 12 are on opposite sides of the front-to-back vertical median plane of the doll body and are spaced somewhat therefrom. They are arranged to pass freely through the respective radial slots 19 in a rocker 20 which is journaled for rocking in a horizontal plane around the rod 21, said rod 21 lying approximately along the vertical "axis" of the doll body. The lower end of the rod 21 fits within an elongated grommet 22 in a hole 23 at the bottom of the doll body. A spring 24 surrounds the grommet 22 and urges it upwardly (FIGS. 1 and 2), while downward movement of the rod with respect to the grommet is limited by an upset projection or projections 25 on the rod. The neck opening 2 of the doll body is bridged by an upwardly concave plate 26 having a hole 26' near its center to receive the upper end 21' of the rod 21. A spring 27 surrounds the rod just below the plate 26 and bears against said plate and a washer or the like 28 secured against downward movement on the rod by a projection or projections 29; the spring 27 tends to urge the rod downward and thus keeps the top of the grommet 22 always in contact with the projection or projections 25. Assuming that the doll body and mechanism as shown in FIGS. 1 and 2 represents a correctly dimensioned assembly in its normal condition it will be seen that vertical elongation of the body, from any cause, is compensated for by expansion of the spring 27 as the upper end 21' of the rod moves downwardly in the hole 26', while vertical contraction or compression is compensated for by compression of the spring 27 and, eventually, of the spring 24 if necessary. This arrangement also makes the installation of the mechanism in the body quite a simple operation, and makes it possible to use accurately uniform mechanical units in doll bodies which may not be so uniform (e.g., because of the difficulty of maintaining close tolerances in a relatively large hollow molded plastic body).

While engagement of the rivet heads 16' in holes or depressions 17 may suffice to keep the legs firmly in standing (walking) position, it is sometimes desirable to prevent positively any unnatural backward bending. This can be accomplished by providing an upwardly projecting stop 30 on each disc 10 in a position such that it may bear against the rear edge of the part 12' of each lever 12, as shown in FIG. 2.

In operation, it will be evident that the interconnection of the legs through discs 10, levers 12 and rocker 20 will cause either leg to move forward or back in a direction, and to an extent, which is complementary to the motion given the other leg, as is customary in walking mechanisms of this type. Either leg, or both legs, can be moved forward to a kicking or sitting position by applying sufficient force to cause the rivet heads 16' to ride out of their respective holes or depressions 17 (against the pressure of springs 18), the rounded rivet heads then merely sliding on the surface of the discs 10 to any

3

desired adjusted position. When moved forward to a sitting position the legs will separate slightly because they rotate around the inclined axes perpendicular to the planes of the steeply slanted leg openings; such separation of the legs (widest at the feet) enables the doll to be set on a flat surface without danger of falling sideways. Because the legs are "journaled" directly in the leg openings of the body it is not necessary to provide additional supports or leg mounting members as in Garidel and Rogovin Patent No. 2,736,135, for example, and the only part of the mechanism supported directly on the body is the rocker rod 21 with its grommet 22 and plate 26 arranged, as noted above, to compensate for a substantial range of variations in the length of the body. The plate 26 is shown and described as bridging the neck opening 2 so as to form a support for the upper end 21' of the rod 21; if the doll body should be of a type having no neck opening, the plate 26, in the same form or suitably modified could still be used, or the rod could be similarly supported in the upper portion of the doll body serving as a structural equivalent for the plate.

It will be understood that various changes may be made in the form, construction and arrangement of the several parts without departing from the spirit and scope of the invention.

What I claim is:

1. A doll and walking mechanism therefor comprising, a hollow doll body having circular leg openings and an upper portion, legs journaled in said leg openings, each leg having a substantially circular aperture in its upper end, and walking mechanism having some elements mounted on each of said legs and some elements mounted on said body, the elements mounted on each leg including a base part in the form of a metal disc extending across the circular aperture, projections integral with said disc and extending through the aperture to engage said disc and fix the disc thereto, a lever rotatably secured to said base part for rotation about the axis of rotation of the leg and extending upward into the doll body, and means for frictionally resisting relative rotation of said lever and said base part, and the elements mounted on the body including a rocker engaging the upwardly ex-

tending parts of the levers and an axle on which the rocker is mounted.

2. A doll and walking mechanism according to claim 1 which includes a positive stop means projecting upwardly from the base part for limiting the movement of the lever relative to the disc in one direction.

3. A doll and walking mechanism according to claim 1 in which the rocker axle is a rod extending lengthwise of the doll body from a point adjacent the bottom of the body to a point adjacent the neck opening and terminating at said points, and which includes rod mounting means permitting limited axial movement of said rod.

4. A doll and walking mechanism according to claim 3 in which the rod mounting means includes an elongated grommet slidably fixed in a hole in the bottom of the doll body and a spring urging said grommet inwardly, the rod being fitted in the bore of the grommet and being provided with a stop to limit its penetration of said bore.

5. In a doll walking mechanism, a sub-assembly which includes a metal disc, projections integral therewith and extending therefrom and adapted to be bent into engagement with a doll leg to fix the disc thereon, a pin having one end fixed to the center of the disc and having a head at its other end, a lever having a part lying parallel to the plane of the disc and pivotally mounted on the pin and a part extending angularly away from the disc, and a spring bearing at one end against the head of the pin and urging the first named lever part strongly toward the disc.

6. In a doll walking mechanism, a sub-assembly according to claim 5 which includes a positive stop means projecting upwardly from the disc in a position to limit the rotative movement of the lever relative to the disc in one direction.
